UNITED STATES PATENT OFFICE.

GEORGE SAMUEL JAMES, OF WESTCLIFF-ON-SEA, ENGLAND, ASSIGNOR OF ONE-HALF
TO HENRY HARRIS LLOYD, OF LONDON, ENGLAND.

CINEMATOGRAPHIC APPARATUS.

Application filed January 24, 1924. Serial No. 688,264.

This invention relates to cinematographic apparatus of the kind in which a continuous band of film is guided into and drawn off from a coil of film resting on its edge on a 5 rotary table, the film being led to the outer laps of the coil and drawn off from the inner laps, or led to the inner laps and drawn off from the outer laps, so that the length of film in the coil remains substantially constant whilst the apparatus is in operation. The said invention comprises improved means for keeping the inner laps of the coil wound in close formation within the laps wound outside them and for preventing the 15 diameter of the inner lap from being reduced to less than a predetermined length.

According to this invention a series of rollers arranged in a circular row are provided mounted on axes extending perpendicularly or nearly perpendicularly to the film receiving surface of the said rotary table. These axes are mounted to slide in slots extending radially or substantially radially from the axis of the table and are 20 urged towards the outer ends of the slots by springs. The slots may be formed in the rotary table, or in a separate plate or frame which may be stationary or movable. The rotary table may be formed by a single disc 25 or it may be divided concentrically into separate parts each of which may be rotated independently of the other parts so that the rotational effort transmitted to any part of the film may vary as this part of the film 30 moves radially to different positions on the table.

With this arrangement, when the tension on the inner laps of the coil of film increases above a predetermined amount so that these 40 laps tend to move inwards away from the surrounding laps, then the rollers will be moved inwardly in the slots, but as soon as the tension in the film decreases the rollers will move outwardly carrying the inner laps 45 of the coil with them. In order to prevent the formation of loose loops of film near to the coil on the table due to slackness of the film, suitable film tensioning devices may be provided.

50 The invention is hereinafter described as applied to cinematographic apparatus of the cabinet type in which the coil supporting rotary table together with suitable optical devices are arranged in a cabinet having a mirror and screen mounted therein so that a

light ray projected vertically upward in the cabinet by the optical apparatus is reflected horizontally outwards from the cabinet.

In the accompanying drawings:—

Figure 1 shows in sectional elevation a 60 cabinet enclosing film carrying mechanism in accordance with this invention.

Figure 2 is a view, on a larger scale, of the rotary table, optical projection apparatus and film tensioning device shown in Figure 1, the rotary table being shown in central section, and

Figure 3 is a plan thereof.

Figure 4 is a detail view of a film lubricating device hereinafter referred to. 70

Figure 5 is a sectional view and Figure 6 is a plan illustrating a modified construction of the rotary table.

Figure 7 is a view similar to Figure 5 illustrating a further modified arrangement 75 of the rotary table, and Figure 8 is a detail plan view of a slide block mounted in the said table.

Referring to Figure 1, 10 is a cabinet enclosing an optical projection apparatus 11 80 by which light is projected upwardly towards a frame 12 hinged to the cabinet at 13 and carrying a mirror at 14 and a screen either at 15 or 16 so that the projected light focussed on the screen is visible from outside 85 the cabinet. The frame 12 can be lowered about the hinge 13 into the cabinet and covered with a lid 17 which can be shut when the apparatus is not in use. A film supporting rotary table 18 with its surrounding 90 guard rim 19 and a film tensioning device comprising a jockey pulley 20 are mounted within this cabinet. To prevent the interior of the cabinet from becoming excessively hot by heat radiated from the projection 95 apparatus 11 and its motor 21, a fan 22 is arranged to draw air away from the heated parts and to discharge it through a pipe 23 which conducts it to the outside of the cabinet. 100

The rotary table 18 is shown built up of concentric parts 18, 18^a, 18^b, (Figures 2 and 3) which are individually driven by toothed gearing 24, 25, as shown, or by any other suitable driving connections arranged to impart different speeds to each part of the table as required either in the same or in opposite directions. If desired the upper surface of the table may be made of any suitable contour in cross section, and a unitary table may 110

be substituted for one comprising concentric parts as shown.

A frame 31 hereinafter described supports guard arms 26 extending above the coil of film 27 on the table and the film at one part of its path of travel is guided to or from the table through a gap in the guard rim 19 between rollers 28. Near to these rollers the casing 19 supports holders 29 (Figure 4) for wax, graphite, or other solid lubricant 30 over which the borders, or those parts of the film which are usually perforated with sprocket holes, are drawn to lubricate the film and to preserve its suppleness.

The frame 31 comprising an upper and a lower ring or plate is held against rotation by an arm 32 connected to a link 33 pivotally mounted on the guard rim 19. This frame 31 has a circular movement imparted to it by an eccentric 34 formed on the table 18 around a central aperture 35 therein, and the said frame has a circular row of radial slots 36 formed therein in which pins 37 are mounted to carry rollers 38. The pins 37 are held at the outer ends of the slots 36 by springs 39.

The film 27 is lapped around the rollers 38 which prevent the inner laps of the coil thus formed from being pulled away from the laps next surrounding them, and so long as the tension on the inner laps of the film does not exceed a certain amount the pins are held in a circular row at the outer ends of the slots. When the tension on the inner laps exceeds a certain amount the springs 39 yield allowing movement of the rollers towards the centre of the table up to a distance limited by the length of the slots 36 thus limiting the reduction of the diameter of the innermost laps. When the tension subsequently decreases, the springs return the rollers to the outer ends of the slots thereby opening out the inner laps of the coil. The rollers 38 may be conical, or concave or of any suitable shape and some of the rollers may be of a different shape from that of the adjacent rollers. The pins 37 are shown set substantially at right angles to the surface of the table 18 but each or any of the rollers may be inclined at any convenient angle.

The part of the film bent out from the inner coil may pass between two rollers mounted in the frame 31 and these rollers are preferably conical or arranged at a convenient angle with reference to the table 18 to allow for the required change of direction of the film.

In apparatus of the type herein referred to, as is well known, the film is rotated by frictional contact with the table so that with a unitary table the laps of the coil tend to rotate at an equal angular velocity but the circumferential length of the outer lap exceeds that of the inner lap so that if equal

lengths are added to and taken from the coil at opposite ends respectively the angular velocities of the different laps must differ correspondingly. Thus there is a varying amount of slip throughout the coil but this slip is itself liable to variations whereby loops of film not under tension may form near the ends of the coil. To prevent inconveniences which may arise from the formation of such loops the film guided to and from the optical apparatus over guide pulleys 38 is kept in tension by one or more jockey pulleys provided where requisite. As shown a jockey pulley 20 is carried by an arm 41 pivoted at 42 and loaded with a weight 43. A spring may be used to move the jockey pulley, the pivot of which can be movably mounted in a guideway instead of being carried on a pivoted arm. By forming the table 18 with a central aperture 35 the optical apparatus 11 can be placed in line below the said table and the projected beam of light passed through this aperture to the screen. This provides a very compact construction. The film 27 passing across the line of projection is guided by two pairs of rollers 43^a and 43^b arranged in line and on opposite sides of the line of projection, as will be understood from a consideration of Figs. 2 and 3.

Instead of the eccentric 34 formed around the aperture 35 in the table 18, the table may be made without this aperture, as shown in Figures 5 and 6, and then the lower ring or plate of the frame 31 may be provided with a cross bar 44 having a hole therein to accommodate a pin 45 holding the frame concentric with the table, or movable into any one of a series of eccentric holes 46 in the table to serve as a crank pin for imparting circular movement to the frame 31 held against rotation by the arm 32 and link 33.

In a further modified arrangement illustrated in Figures 7 and 8, instead of mounting the rollers 38 in a frame separate from the table, the roller pins 37 are mounted in slide blocks 47 moved outwardly in slots 48 formed in the table by springs 49. In the case of a table comprising concentric parts, the part in which the blocks 47 are slidably mounted can be held against rotation. This construction allows the table to be provided with a central aperture similar to the aperture 35 in the table shown in Figure 2.

I claim:

1. Cinematograph apparatus comprising an optical projection apparatus, a rotary table mounted above said projection apparatus and having an aperture in alignment with the optical center of said projection apparatus, means for guiding a continuous band of film edgewise on to and from the table, a circular row of rollers around which the film is lapped and which are supported substantially perpendicular to the table,

yielding supports arranged to allow movement of the rollers radially with reference to the said table, and means for keeping under tension parts of the film passing from 5 and returning to the table.

2. Cinematographic apparatus comprising an optical projection apparatus, an apertured rotary table mounted above said projection apparatus, with the aperture in alignment 10 with the optical centre of said projection apparatus, means for guiding a continuous band of film edgewise onto and from the table, a circular row of rollers around which the film on the table is lapped, and 15 means for keeping under tension parts of the film passing from and returning to the table.

3. Cinematographic apparatus comprising an optical projection apparatus, an apertured rotary table mounted above said projection apparatus, with the aperture in alignment 20 with the optical centre of said projection apparatus, means for guiding a continuous band of film edgewise onto and from the table, a circular row of rollers around 25 which the film on the table is lapped, and means for applying tension to parts of the film not lapped around the said rollers.

4. In cinematographic apparatus, an optical projection apparatus, an apertured 30 rotary table mounted above said projection apparatus with the aperture in alignment with the optical centre of said projection apparatus, said table comprising concentric parts, means for guiding a continuous band 35 of film edgewise on to and from the table, a circular row of rollers around which the film is lapped and which are supported substantially perpendicular to the table, pins on 40 which the rollers are rotatably mounted, means for supporting the said pins so that they are movable radially with reference to the axis of the table, and means for applying tension to the parts of the film leaving and returning to the laps around the rollers.

5. In cinematographic apparatus, an optical projection apparatus, an apertured rotary table comprising concentric parts mounted above said projection apparatus with the aperture in alignment with the optical centre 45 of said projection apparatus, means for rotating each part of said table independently, a row of rollers mounted above the said table, radially movable supporting means for the said rollers, means for guiding a continuous length of film to and from a coil of 50 film around the said rollers, and means for taking up slackness at parts of the film not in said coil.

6. In cinematographic apparatus, an optical projection apparatus, an apertured table 60 rotatably mounted above the projection apparatus with the aperture in alignment with the optical centre of said projection apparatus, a row of rollers mounted above the 65 said table, radially movable supporting

means for the said rollers, a movable frame carrying said supporting means, means for guiding a continuous length of film to and from a coil of film formed around the said rollers, and means comprising the table as a 70 driving element for transmitting a gyratory movement to the said frame.

7. In cinematographic apparatus, an optical projection apparatus, an apertured table rotatably mounted above the projection 75 apparatus with the aperture in alignment with the optical centre of said projection apparatus, a circular row of rollers mounted above the said table, a radially movable supporting means for each roller individually, 80 a movable frame carrying said supporting means, means for guiding a continuous length of film to and from a coil of film formed around the said rollers, and means for imparting a gyratory movement to the 85 said frame from the rotary table.

8. In cinematographic apparatus, an optical projection apparatus, an apertured table rotatably mounted above the projection apparatus with the aperture in alignment 90 with the optical centre of said projection apparatus, a circular row of rollers mounted above the said table, a radially movable supporting means for each roller individually, 95 a movable frame carrying said supporting means, means for imparting a gyratory movement to the said frame from the rotary table, a link connection to a fixed part to prevent rotation of the frame, and means for guiding a continuous length of film to and from a coil of film formed around the said 100 rollers.

9. In cinematographic apparatus, an optical projection apparatus, an apertured table 105 rotatably mounted above the projection apparatus with the aperture in alignment with the optical centre of said projection apparatus, a circular row of rollers mounted above the said table, a radially movable supporting means for each roller individually, 110 a movable frame carrying said supporting means, means for imparting a gyratory movement to the said frame from the rotary table, a link connection to a fixed part to prevent rotation of the frame, means for guiding a continuous length of film to and from a coil of film formed around the said rollers, and means for taking up slackness at parts of the film not in the said coil.

10. In cinematographic apparatus, an optical projection apparatus, an apertured table 120 rotatably mounted above the projection apparatus with the aperture in alignment with the optical centre of said projection apparatus, a circular row of rollers mounted above the said table, guide pulleys arranged to conduct a continuous length of film to and from a coil of film formed around the said rollers, radially movable supporting 125 means for individual rollers arranged to 130

- move inwardly under the tension of the film, and a movably supported jockey pulley arranged to take up slackness at parts of the film not in the said coil.
- 5 11. In cinematographic apparatus, an optical projection apparatus, an apertured rotary table comprising independently rotatable parts mounted above the projection apparatus with the aperture in alignment with the optical centre of said projection apparatus, means for rotating each part of said table separately, a circular row of rollers mounted above the table on supports separately movable radially with respect to the 15 axis of the table, guide pulleys arranged to conduct a continuous length of film to and from a coil of film formed around the said rollers, a pivoted counterweighted arm and a jockey pulley carried by said arm and 20 pressed against the film by the counterweight.
12. In cinematographic apparatus, an optical projection apparatus, an apertured table rotatably mounted above the projection apparatus, with the aperture in alignment with the optical centre of said projection apparatus, a circular row of rollers supported above the table, means for guiding a continuous length of film to and from a coil formed around the rollers, movable supporting means for individual rollers arranged to move radially outwardly under the action of springs and inwardly under the tension of the film, means for maintaining under tension parts of the film outside the said coils, 35 and a stationary guard rim around the edge of the said table.
13. In cinematographic apparatus, an optical projection apparatus, an apertured table rotatably mounted above the projection apparatus, with the aperture in alignment with the optical centre of said projection apparatus, a circular row of rollers mounted above the said table, a radially movable supporting means for each roller individually, a movable frame carrying said supporting means, means for imparting a gyratory movement to the said frame from the rotary movement of the table, a stationary guard rim around the said table, a link connection 40 between the movable frame and the stationary rim, and means for guiding a continuous length of film to and from a coil of film formed around the said rollers.
- 45 50 55 14. In cinematographic apparatus, an optical projection apparatus, an apertured table rotatably mounted above the projection apparatus, with the aperture in alignment with the optical center of the said projection apparatus, a circular row of rollers mounted above the table around the said aperture, radially movable supporting means for the said rollers, and means for guiding a continuous length of film to and from a coil of film formed around the said rollers.
- 60 65 70 75 80 85 90 95 100 105 110
15. In cinematograph apparatus, an optical projection apparatus, an apertured table rotatably mounted above the projection apparatus with the aperture in alignment with the optical centre of said projection apparatus, a stationary guard rim around the edge of the said table, a circular row of rollers mounted above the table around the said aperture, radially moving supporting means for the said rollers, and means for guiding a continuous length of film to and from a coil formed around the said rollers into alignment with the optical centre of the said projection apparatus.
16. In cinematograph apparatus, an optical projection apparatus, an apertured table comprising concentric parts rotatably mounted above the projection apparatus with the aperture in alignment with the optical centre of said projection apparatus, means for independently rotating the concentric parts of said table, a stationary guard rim around the edge of the said table, a circular row of rollers mounted above the table around the said aperture, radially moving supporting means for the said rollers, and means for guiding a continuous length of film to and from a coil formed around the said rollers into alignment with the optical centre of the said projection apparatus.
17. In a cinematograph, a projection apparatus, a rotary table comprising a central disc and a series of rings arranged concentrically around said disc, means for independently rotating each part of said table, a circular row of rollers arranged above and within the area of said disc portion of the table, radially yielding supports arranged to allow movement of said rollers, means for simultaneously feeding film edge-wise on to and off from a coil of film lapped around said rollers, a stationary guard rim around the edge of said table guide rollers for the film mounted on said stationary guard rim, and means for guiding the film fed from the coil on said table into alignment with the optical centre of said projection apparatus.

GEORGE SAMUEL JAMES.
